UNITED STATES PATENT OFFICE.

OSCAR F. ONKEN, OF CINCINNATI, OHIO.

DESIGN FOR A DISPLAY-FIXTURE.

44,585.

Specification for Design.

Patented Aug. 26, 1913.

Application filed June 28, 1913. Serial No. 776,438. Term of patent 3½ years.

To all whom it may concern:

Be it known that I, OSCAR F. ONKEN, a citizen of the United States, and residing at Cincinnati, Hamilton county, State of Ohio, have invented a certain new, original, and ornamental Design for Display-Fixtures, reference being had to the accompanying drawing, which shows my design in perspective view.

I claim—

The ornamental design for a display fixture, as shown.

OSCAR F. ONKEN.

Witnesses:

C. SPENGEL,
T. LE BEAU.
